UNITED STATES PATENT OFFICE.

HARRY C. GAWNE, OF LAKewood, OHIO.

FREIGHT CAR.

Application filed December 11, 1924. Serial No. 755,190.

My invention relates to freight cars and particularly to freight cars designed to carry poultry or similar freight and the principal object of my invention is to so 5 form a car of this type that the compartments provided for the poultry or other freight may be readily folded against the walls of the car to permit use of the car for other purposes. In the drawings accompanying this specification and forming a part thereof I have shown, for purposes of illustration, one form which my invention may assume. In these drawings:—

Figure 1 is a partial vertical section longitudinally of a freight car showing this illustrative form of my invention,

Figure 2 is a fragmentary section on the line 2—2 of Figure 1,

Figure 3 is a section on the line 3—3 of Figure 2,

Figure 4 is a view similar to Figure 1 showing the compartments folded and the car ready for other use, the screens 37 being omitted for clarity while

Figure 5 is a section on the line 5—5 of Figure 4.

The embodiment of my invention herein illustrated forms the desired compartments by means of a plurality of units 11 each supported from the car side wall and each adapted to coact with either the car end wall or the preceding unit to form a plurality of compartments arranged in a vertical row extending from the car floor to the car inner ceiling and adapted to receive poultry or other freight of such kind that shipment in compartments is desirable.

Each of these units 11 is herein shown as comprising a rib 12 secured to the car side wall 13 and carrying pivoted thereto at 14 a cross partition 15 to which is pivoted at 17 a longitudinal partition 18 extending, when the unit is open, from the cross partition 15 to either the car end wall 19 or the preceding cross partition 15. Pivoted at 20 to the car side wall 13 are a plurality of floor plates 21 each adapted to be swung upwardly against the car side wall 13 or dropped downwardly into position resting upon lugs 22 carried by the ribs 12, as shown in Figure 2, and arranged to act in cooperation with the corresponding lip 24 carried by the longitudinal partition 18 to support a plurality of floor plates 25 and 26 and 27 of which the plates 25 and 26 are hinged together at 28, the

plates 26 and 27 are hinged together at 29, and the plate 27 is hinged at 30 to the cross partition 15 and carries a water trough 31 rigidly secured thereto.

In order to hold the cross partition 15 and the longitudinal partition 18 firmly in position I provide the free ends of these partitions with bolts 32 arranged to enter corresponding apertures 33 in the inner car roof 34 and in the car floor 35, in order to facilitate ventilation I provide the cross partition 15 with a plurality of apertures 36 each closed by a wire netting 37 effective to prevent shifting of material from one compartment 38 to a compartment laterally adjacent thereto, and in order to afford access to each compartment 38 I provide the longitudinal partition 18 with a plurality of doors 39 pivotally connected thereto and adapted to be closed to close the compartments 38 or opened to afford free access to the compartments 38.

It will be apparent from the above description that each unit 11 coacts with either the car end wall 19 or the cross partition 15 of the previous unit to form a plurality of compartments each formed by the car side wall 13, the cross partition 15 of the particular unit 11, the longitudinal partition 18 of that unit, the car end wall 19 or the cross partition 15 of the preceding unit, the car floor 35 or a floor unit consisting of floor sections 21 and 25 and 26 and 27, and one of these floor units or the inner car top 34, and each of an extent perpendicularly to the car side wall 13 greater than the height of the compartment. It will also be apparent that each of these compartments is completely suitable for the purposes for which it was designed. In addition, it will be obvious to those skilled in the art that when it is desired to use the car for the shipment of freight for which compartments are not desired each of the units 11 may be folded against the car side 13 by folding up the sets of floor sections 25, 26, and 27 against the cross partition 15 and securing the sets in that position by means of the hooks 40, folding the floor sections 21 against the car side wall 13, withdrawing the bolts 32 from the car floor 35 and inner car ceiling 34, folding the longitudinal partition 18 about the hinges 17 against the cross partition 15, folding the cross partition 15 and the parts secured thereto about the hinges 14 against the

car side wall 13, and finally securing the parts in this position by inserting into suitable apertures 41 in the car floor 35 and inner car top 34 the bolts 32 carried by the free end of the cross partition 15.

I have disclosed herein one form which my invention may assume and set forth either specifically or inferentially various advantages of that particular form. At the same time, those skilled in the art will find additional advantages in my invention and in the form thereof herein disclosed and in addition will realize that the particular embodiment of my invention which I have presented herein may be variously changed and modified without departing from the spirit of my invention or sacrificing the advantages thereof. It will therefore be understood that the disclosure herein is illustrative only and that my invention is not limited thereto.

I claim:

1. A freight car comprising a side wall and a plurality of partition units arranged along said side wall, each of said units comprising a first vertical wall pivoted to said side wall and arranged to extend substantially at right angles to said side wall and transversely of said car, a second vertical wall pivoted to said first vertical wall and arranged to extend substantially parallel to said side wall and longitudinally of said car into engagement with a wall section effective to form the fourth vertical wall of a four walled enclosure, such as the car end wall or the first vertical wall of a preceding unit, and a plurality of vertically spaced horizontal walls hinged to one of said vertical walls and arranged to divide such enclosure into a vertically extending series of compartments, said horizontal walls being foldable against the vertical wall to which they are hinged, and said vertical walls being foldable with said horizontal walls against said side wall.

2. A freight car comprising a side wall and a plurality of partition units arranged along said side wall, each of said units comprising a first vertical wall pivoted to said side wall and arranged to extend substantially at right angles to said side wall and transversely of said car, a second vertical wall pivoted to said first vertical wall and arranged to extend substantially parallel to said side wall and longitudinally of said car into engagement with a wall section effective to form the fourth vertical wall of a four walled enclosure, such as the car end wall or the first vertical wall of a preceding unit, and a plurality of vertically spaced horizontal walls hinged to one of said vertical walls and arranged to divide such enclosure into a vertically extending series of compartments each of an extent perpendicular to the vertical wall to which it is hinged greater than the distance be-

tween it and either adjacent horizontal wall, said horizontal walls being foldable against the vertical wall to which they are hinged, and said vertical walls being foldable with said horizontal walls against said side wall. 70

3. A freight car comprising a side wall and a plurality of partition units arranged along said side wall, each of said units comprising a first vertical wall pivoted to said side wall and arranged to extend substantially at right angles to said side wall and transversely of said car, a second vertical wall pivoted to said first vertical wall and arranged to extend substantially parallel to said side wall and longitudinally of said car into engagement with a wall section effective to form the fourth vertical wall of a four walled enclosure, such as the car end wall or the first vertical wall of a preceding unit, and a plurality of vertically spaced horizontal walls hinged to one of said vertical walls and arranged to divide such enclosure into a vertically extending series of compartments, said horizontal walls being foldable against the vertical wall to which they are hinged, said vertical walls being foldable together to enclose said horizontal walls, and said vertical walls being foldable with said horizontal walls against said side wall. 85

4. A freight car comprising a side wall and a plurality of partition units arranged along said side wall, each of said units comprising a first vertical wall pivoted to said side wall and arranged to extend substantially at right angles to said side wall and transversely of said car, a second vertical wall pivoted to said first vertical wall and arranged to extend substantially parallel to said side wall and longitudinally of said car into engagement with a wall section effective to form the fourth vertical wall of a four walled enclosure, such as the car end wall or the first vertical wall of a preceding unit, and a plurality of vertically spaced horizontal walls hinged to one of said vertical walls and arranged to divide such enclosure into a vertically extending series of compartments, said horizontal walls being foldable against the vertical wall to which they are hinged, and said vertical walls being foldable with said horizontal walls against said side wall and with said first vertical wall enclosing the entire unit. 105

5. A freight car comprising a side wall and a plurality of partition units arranged along said side wall, each of said units comprising a first vertical wall pivoted to said side wall and arranged to extend substantially at right angles to said side wall and transversely of said car, a second vertical wall pivoted to said first vertical wall and arranged to extend substantially parallel to said side wall and longitudinally of said car into engagement with a wall section effective to form the fourth vertical wall of 125 130

a four walled enclosure, such as the car end wall or the first vertical wall of a preceding unit, and a plurality of vertically spaced horizontal walls hinged to said first vertical wall and arranged to divide such enclosure into a vertically extending series of compartments, said horizontal walls being foldable against the vertical wall to which they are hinged, and said vertical walls being foldable with said horizontal walls 10 against said side wall.

In testimony whereof, I hereunto affix my signature.

HARRY C. GAWNE.
